UNITED STATES PATENT OFFICE.

OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed March 1, 1922. Serial No. 540,134.

My invention relates to circuit interrupters and more particularly to means for controlling the formation of arcs that are established when an interrupter is opening and to means for extinguishing such arcs.

In breaking circuits of high amperage, the interruption thereof is facilitated if a plurality of arcs are established between the relatively movable contact members. The concentration of an arc at a single point tends to overheat and cause a rapid deterioration of the contact members. This tendency towards concentration is present even though a plurality of arcing tips are provided in connection with each of the contact members. Heretofore, no provision has been made to secure a temporary stability of arcs across such arcing tips, with the result that the arcing would usually take place across a single pair of relatively movable tips.

One of the objects of my invention is to provide means for establishing a plurality of arc streams between relatively movable contact members and to insure the temporary stability of such streams.

Another object of my invention is to provide means whereby the arcs that are formed may be more readily extinguished.

As shown in the accompanying drawing, Figure 1 is a view, in side elevation, of a portion of a circuit breaker embodying my invention.

Fig. 2 is a view thereof in side elevation, and

Fig. 3 is a detail view of the main portions of a modified form of the device shown in Figs. 1 and 2.

The apparatus comprises a pair of conductor members 5 and 6 having brush contact members 7 and 8, respectively, that are bridged by a movable contact or bridging member 10 which is operated through the medium of a lifting rod 11. These portions of the apparatus may be of any standard type.

The respective conductor members 5 and 6 support pairs of arcing tips 12 and 13, through the medium of brackets 14 and 15 that are provided with arms 16 and 17.

The bridging member 10 supports two pairs of arcing tips 19 and 20, upon pivots

21 and 22, respectively, the arcing tips 19 and 20 being normally biased upwardly by resilient members 24 and 25, so that they may be maintained in engagement with the 55 arcing tips carried by the conductors 5 and 6 until after the bridging member 10 has moved a predetermined distance from the stationary contact members 7 and 8.

The arms 16, that support the arcing tips 60 12, and the arms 17, that support the arcing tips 13, are respectively provided with iron collars 28. The members 28 serve to produce inductive reactances in the local arcing contact circuit and thereby increase the 65 stored energy as well as the impedance of the circuits through the arcing tips 12 and 13, respectively.

As shown more clearly, in Fig. 2, the arcing tips 12 are connected in parallel, and 70 the impedance created by the members 28 serves to insure an approximately equal current division between contact circuits preceding the arc formation. Upon separating arcing contacts, the stored energy and impedance of each parallel arcing circuit will insure sufficient stability temporarily in each arc to substantially maintain the initial current division secured in the arcing circuit.

In the modified form shown in Fig. 3, the 80 arms 16 and the iron collars 28 are omitted. In this latter construction, the brackets 14 and 15 are severally provided with a pair of curved portions 30 through which current flows to a pair of arcing tips 32 that 85 co-operate with a pair of arcing tips 33 carried by the bridging member 10.

The loops 30 function in somewhat the same manner as do the members 28, in that they provide an impedance whereby the current through the parallel-connected arcing tips 32 is equalized. They also perform a further function in that the flow of current through such loops and the arcing tips 32 and 33 traverses a return path, thereby 95 setting up a magnetic field between the upwardly directed portion of the loops 30 and the adjacent faces of the contact members 32 and 33 and exercising a blow-out effect on arcs that may be formed between the 100 arcing tips 32 and 33.

It will be understood that, in Fig. 3, I

have shown only substantially one-half of the apparatus, the other half being the same as that shown in Fig. 1, except for the looped conductors 30.

5 It will also be understood that an end view, looking from the right of Fig. 1, will be identical with the view of Fig. 2, and that a view from either end of Fig. 3 would also be substantially identical with that of Fig. 2.

10 Referring again to Figs. 1 and 2, upon the separation of the arcing tips 19 from the arcing tips 12, for example, arcs will be formed, and, by reason of the presence of members 28 which equalize the flow of current through the tips 12, the two arcs will be maintained for substantially the same period and will be extinguished at substantially the same instant.

15 20 It will be clear that, in the device of Fig. 3, the arcs are maintained in substantially the same manner as in the device of Fig. 2, and that, in addition, the magnetic field set up between the loops 30 and the arcs adjacent thereto will exercise a blow-out effect upon the arc and will assist in extinguishing the same.

25 30 Various modifications may be made in the device, such as by employing more than two sets of arcing tips at each side of the apparatus.

I claim as my invention:

35 1. The combination with a pair of stationary contact members and a bridging member therefor, of a pair of arcing tips connected to each of the said contact members, two pairs of arcing tips carried by the bridging member in position to co-operate with the first mentioned arcing tips, and impedance means in each of the first mentioned arcing-tip circuits for equalizing the currents traversing the same.

40 45 50 2. The combination with a pair of stationary contact members and a bridging member therefor, of a pair of arcing tips connected to each of the said contact members, two pairs of arcing tips carried by the bridging member in position to co-operate with the first mentioned arcing tips, and means for equalizing the currents traversing the arcing tips.

55 60 65 3. The combination with a pair of stationary contact members and a bridging member therefor, of a pair of arcing tips connected to each of the said contact members, two pairs of arcing tips carried by the bridging member in position to co-operate with the first mentioned arcing tips, and an inductive circuit associated with one of each two co-operating arcing tips.

4. The combination with a pair of stationary contact members and a bridging member therefor, of a pair of arcing tips connected to each of the said contact members, two pairs of arcing tips carried by the

bridging member, one pair at each of its ends, in position to co-operate with the first mentioned arcing tips, and an arc-extinguishing device associated with one of each two co-operating arcing tips.

5. The combination with a pair of stationary contact members and a bridging member therefor, of a pair of arcing tips connected to each of the said contact members, two pairs of arcing tips carried by the bridging member in position to co-operate with the first mentioned arcing tips, and a combined arc blow-out and impedance device associated with one of each two co-operating arcing tips.

6. The combination, with a plurality of stationary contact members that are connected in parallel and a movable contact member for engagement therewith, of a combined arc blow-out and impedance device associated with each of said stationary contact members.

7. The combination with two relatively movable main contact members, of a pair of arcing tips carried by one of said members and connected in parallel, and means for equalizing the current through the arcing tips.

8. The combination with two relatively movable main contact members, of a pair of arcing tips carried by one of said members and connected in parallel and means for equalizing the current through the arcing tips, said means serving also as an arc blow-out device.

9. The combination with a pair of stationary contact members and a bridging member therefor, of a pair of arcing tips connected to each of the said contact members, two pairs of arcing tips carried by the bridging member in position to co-operate with the first mentioned arcing tips, and impedance means in each of the first mentioned arcing-tip circuits for maintaining equal current division therein.

10. The combination with a pair of stationary contact members and a bridging member therefor, of a pair of arcing tips connected to each of the said contact members, two pairs of arcing tips carried by the bridging member in position to co-operate with the first mentioned arcing tips, and energy-storage means in each of the first mentioned arcing-tip circuits for securing temporary arc stability.

11. The combination with a pair of stationary contact members and a bridging member therefor, of a pair of arcing tips connected to each of the said contact members, two pairs of arcing tips carried by the bridging member in position to co-operate with the first mentioned arcing tips, and means for creating and maintaining equalization of currents that traverse the arcing tips.

12. A pair of main contacts, a plurality of sets of arcing contacts cooperating with said main contacts, and impedance means in series with each set of arcing contacts.

5 13. A pair of main contacts, a plurality of sets of arcing contacts cooperating with said main contacts, and a magnetic ring sur-

rounding a lead to each set of arcing contacts.

In testimony whereof, I have hereunto subscribed my name this 15th day of February, 1922.

OTTO H. ESCHHOLZ.
